UNITED STATES PATENT OFFICE

VICTOR JAKOB, OF RACINE, WISCONSIN

SPEED REGULATOR FOR PHONOGRAHS

Application filed October 11, 1926. Serial No. 140,913.

This invention relates to speed regulators for phonographs.

In phonographs of the usual type, it is the customary practice to rotate the record carrying table at a constant speed, although the linear travel of the stylus is greater at the outer periphery of the record than at its inner periphery. The result of this construction is that the outer portion of the record travels very much faster than is required and, consequently, the length of the record is unnecessarily shortened.

Objects of this invention are to provide a novel form of mechanism for driving the table of a phonograph so that the travel of the record with respect to the stylus is at the same rate at the outer periphery of the record as at the inner periphery of the record or, in other words, to provide means which gradually varies the speed of rotation of the table, as the stylus shifts its radial position with respect to the center of the table, so that the linear speed is at all times constant.

In view of the fact that nearly all records as now made are adapted for use on phonographs in which the table rotates at a constant speed, this invention has for its further object the provision of means for quickly changing the mechanism over from that previously described, into one in which the table is rotated at a constant predetermined number of revolutions per minute, and the automatic varying of the speed is temporarily dispensed with.

Further objects are to provide a mechanism having the characteristics stated above in which the construction is very simple and practical and may be readily produced and easily operated.

An embodiment of the invention is shown in the accompanying drawings in which:—

Figure 1 is a plan view partly in section and partly broken away showing the essential portions of the mechanism for securing the variable rate of rotation for the table;

Figure 2 is a sectional elevation approximately on the line 2—2 of Figure 1, the table and the control mechanism, however, being shown in full lines;

Figure 3 is a side elevation with parts

taken in section along the line 3—3 of Figure 1.

Referring to the drawings, particularly Figures 1 to 3, it will be seen that a record carrying table 1 of the usual type has been illustrated, together with a tone arm 2, and a reproducer 3, pivotally mounted upon the tone arm, such tone arm being free to swing in the usual manner, and said reproducer having the usual stylus 4.

The drive for the table is extremely simple and novel in construction, as will be apparent as the description proceeds. It comprises a driving roller or drum 5 operated or driven by a motor 6, such drum and motor being carried by a pivoted frame 7, the frame being pivoted upon the uprights 8. The free end of the frame is provided with a guiding pin 9, as shown most clearly in Figure 2, and a spring 10 loosely surrounds the pin and carries the weight of the frame and associated parts, washers being preferably provided at the upper and lower ends of the spring. It is to be noted particularly from Figures 1 and 2 that a cam shift member 11 is pivoted at 12, and is provided with a controlling lever 13. This cam shift member is provided with a curved slot 14 which loosely receives the pin 9. It is to be noted from Figures 2 and 3 that one end of the cam shift member is raised and the other end lowered, so that as it is rocked about its pivot point, it raises the frame upwardly into operative position for driving, or lowers it out of driving position.

The roller 5 or drum carries a rubber ring 15 which is of greater internal diameter than the roller, as may be seen from Figure 2. This rubber ring operatively connects the constant speed drum 5 with the lower side of the revoluble table 1.

It is to be noted that the ring 15 may be freely shifted along the drum and means in the form of a lever 16 is provided for shifting this ring, the lever being equipped with spaced fingers or forked ends 17 and 17' above and below the drum which loosely engage the ring. This lever is operated by means of the tone arm through the medium of a lever 18 rigid with the tone arm and a

connecting link 19, as may be seen from Figure 1.

It is to be noted that the construction is extremely simple and may be easily produced. For example, the spindle 20 for the table 1, as shown in Figure 1, may be carried by a bracket 21 and may rest at its lower end upon a bearing pin 22. Further, the lever 16, as may be seen from Figure 2, can easily be carried by a similar bracket 23. However, it is merely necessary to loosely pivot the shaft 24 of the lever 16 within the upper and lower ends of the bracket 23. A bracket 19^a is provided with an upper aperture into which the end of the link 19 may be hooked, as shown in Figure 1, under conditions described in detail hereinafter.

The operation of the apparatus is as follows:

When it is desired to play a record in which the linear speed of the record passing the stylus is to be maintained as, for instance, for a record intended for uniform linear speed of the groove past the stylus of a reproducer, it is merely necessary to rock the controlling lever 13 into the position shown in Figure 1. This raises the pivoted frame 7 and yieldingly presses the ring 15 into contact with the underside of the table 1, and consequently operatively connects the drum and the table. Thereafter, motion of the tone arm 2 in following the record is transmitted to the lever 16, and gradually rocks the lever inwardly, thus moving the ring 15 nearer the center of the rotary table and, consequently, keeping the ring substantially directly under the stylus at all times, and maintaining the linear rate of travel absolutely constant.

If it is desired to play an ordinary type of record, it is merely necessary to unhook the link 19 from the lever 18 and hook it in the bracket 19^a. This rocks the control lever or handle 13 into the position shown in dotted lines in Figure 1. This will cause the phonograph record to be driven at its highest speed.

From actual experiments, it has been found that the driving mechanism for the table requires a minimum amount of effort to shift the ring 15, and, consequently, such construction has been found highly practical and easily controlled from the tone arm.

It will be seen that a novel form of phonograph has been provided which will play records either with a constant linear speed, or else with a variable linear speed as has heretofore been made. Further, it will be seen that the mechanism for securing these results is of the utmost simplicity and is most easily controlled, and offers extremely low frictional resistance.

Further, it will be seen that the mechanism may be easily produced by ordinary machine shop methods and that it is reliable and substantially free from fragile parts.

The term "phonograph" as used in the appended claims is intended to include both the reproducing and the recording machines of this general type.

Although the invention has been described in considerable detail, such description is intended as illustrative rather than limiting as the invention may be variously embodied and as the scope of such invention is to be determined as claimed.

I claim:

1. Driving mechanism comprising a disc, a drum mounted below said disc and having its axis at right angles to the axis of the disc, a friction ring loosely surrounding said drum and adapted to contact with said disc, means for raising or lowering said drum to cause said ring to contact with or move away from said disc, and means for moving said ring towards or away from the center of said disc, whereby the speed of rotation of said disc may be varied.

2. Driving mechanism comprising a disc, a drum mounted below said disc and having its axis at right angles to the axis of the disc, a friction ring loosely surrounding said drum and adapted to contact with said disc, a forked lever having its ends rounded and receiving a portion of said ring immediately in front of the point of contact of said ring and said disc and on the leading side of said disc, and means for moving said lever, whereby said ring bodily pivots about its point of contact during shifting.

3. Driving mechanism comprising a disc, a drum mounted below said disc and having its axis at right angles to the axis of the disc, a friction ring loosely surrounding said drum and adapted to contact with said disc, a forked lever having its ends rounded and receiving a portion of said ring immediately in front of the point of contact of said ring and said disc and on the leading side of said disc, and means for moving said lever, whereby said ring bodily pivots about its point of contact during shifting, said ring being formed of rubber.

In testimony that I claim the foregoing I have hereunto set my hand at Milwaukee, in the county of Milwaukee and State of Wisconsin.

VICTOR JAKOB.
